DESIGN FOR A SHOE

Max Gustin, New York, N. Y.

Application August 9, 1935, Serial No. 58,026

Term of patent 3½ years

To all whom it may concern:

Be it known that I, Max Gustin, a citizen of the United States of America, residing in the Borough of Manhattan, county of New York, State of New York, have invented a new, original, and ornamental Design for a Shoe, for which the following is a specification, reference being had to the accompanying drawing, forming part thereof, wherein,

Figure 1 is a plan view of the shoe showing my new design with upper flexible petals in a curled position.

Figure 2 is a plan view of the shoe showing my design with the upper flexible petals in a flattened position.

Figure 3 is a side elevational view of a shoe, with the upper petals in the same position as shown in Figure 1.

I claim:

The ornamental design for a shoe substantially as shown and described.

MAX GUSTIN.
